United States Patent Office

Des. 185,707

Patented July 21, 1959

185,707

BABY FOOD SERVER

Ruth M. Gallagher, Oceanside, Calif.

Application February 3, 1958, Serial No. 49,475

Term of patent 3½ years

(Cl. D54—12)

Fig. 1

Fig. 2

Fig. 3

I claim:

The ornamental design for a baby food server, as shown.
